UNITED STATES PATENT OFFICE.

ALFRED HEALD, OF PHILADELPHIA, PENNSYLVANIA.

PILE FABRIC AND MODE OF WEAVING SAME.

No. 892,517.

Specification of Letters Patent.

Patented July 7, 1908.

Application filed May 2, 1906. Serial No. 314,862.

To all whom it may concern:

Be it known that I, ALFRED HEALD, a citizen of the United States, residing in Philadelphia, Pennsylvania, have invented 5 certain Improvements in Pile Fabrics and the Mode of Weaving Same, of which the following is a specification.

My invention relates to the production of figured pile fabrics by the operation sometimes termed "double weaving" by which is meant the production of two backing webs with the pile-forming threads or yarns crossing from one to the other, this double web being afterwards severed at a point midway 10 between the two backing webs, so as to produce two cut pile fabrics, and my invention relates especially to the production of such a double web with parti-colored pile warp threads, the object of my invention 15 being to produce two fabrics without increase in the cost of printing the parti-colored warp threads as compared with the cost of printing the same for a single fabric, and without any such increase in the cost of 20 the threads themselves as would naturally be caused by the production of two fabrics 25 instead of one.

In the accompanying drawings:—Figure 1, is a view showing, in a diagrammatic way, 30 the various essential parts of a loom such as I employ in carrying out my invention, this view showing one adjustment of the various warp threads employed in weaving the preferred form of my improved fabric; Figs. 2 and 3, are views similar to Fig. 1 but illustrating the production of modified fabrics in accordance with my invention; Figs. 4 and 5 are exaggerated sections of the double fabrics shown respectively in Figs. 1 and 2, and Figs. 40 6 and 7 are views illustrating other dispositions of warp and weft threads in the backing fabric.

In Figs. 1 to 5 are illustrated the dispositions of successive color units in the parti-colored warp threads employed, and also various dispositions of warp and weft threads in the backing web when what is termed a "two-shot" binder is employed, and Figs. 6 and 7 show different dispositions of the warp 45 and weft threads in the backing web when what is termed a "three-shot" binder is used.

Referring first to Fig. 1 of the drawing, 1 represents the breast beam of a loom, 2 the swinging lay, 3 the reed carried by the same,

4 and 5 upper and lower shuttles, and 6 a 55 fixed reed in the rear of the swinging lay. Mounted upon a bar 7 just behind the breast beam are a series of separator plates of which there are, by preference, as many as there are sets of warp threads employed in the 60 weaving of the fabric, each of these separator plates passing through a space of the reed 3 and engaging the fixed rear reed 6, in order that it may be permanently retained in lateral and vertical position by the latter. 65

The separator plates are, by preference, made in two parts 8 and 9, the part 8 being mounted upon the bar 7, and the part 9 passing through the reeds and having its forward end reduced in thickness to form an upper 70 tongue 10 and an undercut recess in the bottom of the plate, the tongue engaging and being soldered or otherwise secured to the part 8, and the recess receiving the cutting knife 11, whereby the web is separated. By 75 this means the part 8 can be readily punched from sheet metal, and the part 9 rolled from wire, thereby simplifying and cheapening the manufacture of the separator plate.

Through spaces of the swinging reed 3 and 80 fixed reed 6, alternating with those which receive the separator plates, pass the sets of warp threads employed, each set of such warp threads in the fabric shown in Figs. 1 and 4 comprising a parti-colored pile warp 85 thread 12, two stuffer warp threads 13 and 14, one for each backing fabric, and four binding warp threads 15, 16, 17, and 18, two for each of the backing fabrics, the pile warp threads 12 being controlled by a heddle 19, the stuffer warp threads 13 and 14 being controlled by heddles 20 and 21, and the binding warp threads 15, 16, 17 and 18 being controlled by heddles 22 and 23. In connection with these warp threads are employed four weft threads 26, 27, 28 and 29 90 for each backing web, the weft threads of the upper web being introduced by the upper shuttle 4 above the separator plates 9, and the weft threads of the lower web being introduced by the lower shuttle 5 below said separator plates 9. The pile warp threads 12 are shedded alternately above the upper shuttle 4, between the two shuttles, and below the lower shuttle 5, while 95 the stuffer warp threads and the binder warp threads are shedded with reference to single shuttles, the upper stuffer warp thread

13 and the upper binder warp threads with reference to the upper shuttle 4, and the lower stuffer warp thread 14 and the lower binder warp threads with reference to the lower shuttle 5.

5 The weft threads are introduced simultaneously in pairs, one by the upper shuttle and one by the lower shuttle. The weft threads 26 and 27 are binder weft threads, 10 and the weft threads 28 and 29 are separator weft threads, and they are introduced as follows. The warp threads 13, 15 and 17 are first raised and the warp threads 12, 14 and 18 are lowered for the insertion of the weft thread 26 of the lower web, and the weft thread 28 of the upper web. The warp thread 13 is then lowered, the warp thread 14 raised, and the warp thread 12 adjusted to a mid position between the two shuttles 15 for the insertion of the weft thread 27 of the lower web, and the weft thread 29 of the upper web. The warp thread 12 is then 20 fully raised, the warp threads 13, 16 and 18 are raised and the warp threads 14, 15 and 17 lowered for the insertion of the weft thread 28 of the lower web, and the weft thread 26 of the upper web, and the warp thread 13 is then lowered, the warp thread 14 raised, and the warp thread 12 lowered 25 to mid position for the insertion of the weft thread 29 of the lower web and the weft thread 27 of the upper web, and these operations are repeated indefinitely. The pile warp threads 12 are thus interwoven first 30 with the upper web, and then with the lower web, while the stuffer warp threads and binder warp threads are interwoven with weft threads of a single web only. When 35 therefore the pile warp threads which cross from one web to the other are severed at a point intermediate of the two webs by the reciprocating or continuously running transverse knife 11, two complete cut pile fabrics will be produced, which may be led to suitable take-up rolls and thence disposed of in 40 the manner most available.

In preparing the pile warp threads for use in carrying out my improved method of weaving I proceed in the manner usual in preparing such warp threads for what are known as tapestry carpets, and I use no greater length of warp thread than is necessary for producing a single carpet of the usual character, although I may increase 45 the size or number of strands in each thread to an extent equal to, say, 50 per cent. of the number usually employed, this increase in the size of the thread, however, requiring no greater amount of time in the printing of the thread, nor any materially greater amount of dyeing or printing material for the purpose.

50 The minimum length of color unit in an ordinary tapestry warp is of a size sufficient 55 to produce one pile loop, and the minimum

length of color unit in a warp produced in accordance with my invention, is therefore sufficient only to extend from one backing web to the other, hence, when the fabric is cut, changes in the coloring of the pattern 79 can be effected upon single ends of the yarn, as will be noted on reference to Fig. 4, instead of upon a loop of yarn or upon a pair of adjoining ends of the same, as in the ordinary tapestry carpet, and by this means 75 a much finer class of ornament is possible in the pattern than when the ordinary mode of weaving is adopted.

The fact that two shots of weft are introduced simultaneously, one in each backing 80 web, also permits of the weaving of the double fabric more expeditiously than the usual single fabric is woven, owing to the absence of pile wires, hence it will be evident that cut pile fabrics can be produced in accordance 85 with my invention at less expense than by the methods at present in use.

In weaving the fabric shown in Figs. 2 and 5 two warp threads 15 and 17 only are employed, each of these warp threads being interwoven with weft threads 26 and 27 of its respective backing web, the separator weft threads 28 and 29 being omitted, and a weft thread 26 of one web being introduced simultaneously with a weft thread 27 of the other web. In Fig. 2 I have also shown a separator plate 9^a made in one piece instead of 90 the composite separator plate shown in Fig. 1.

In weaving the fabric shown in Fig. 3 there are two pile warp threads 12 and 12^a, and 100 four binder warp threads 15, 16, 17 and 18, a pile warp thread of each set being shedded above the upper shuttle and the other below the lower shuttle, and the two binding warp threads of the upper web being shedded with 105 reference to the upper shuttle and those of the lower web with reference to the lower shuttle, as in Fig. 1, but being interwoven with weft threads 26 and 27, the separator weft threads 28 and 29 being omitted in this 110 case also. In weaving this fabric the two inner or pile-binding weft threads 26 are introduced simultaneously, and the two outer or stuffer-binding weft threads 27 are also introduced simultaneously and in alternation with the inner binding weft threads, the pile threads crossing each other in their passage from one web to the other.

All of the webs shown in Figs. 1 to 5 employ what is known as a "two-shot" binder, 120 but I may, in weaving my improved fabric, employ what is known as a "three-shot" binder, in which each set of weft threads comprises three threads which may be disposed one on the inside of the web and two 125 on the outside, as in Fig. 6, or one on the outside and two on the inside, as in Fig. 7.

I claim:

1. A woven fabric having a cut pile composed of parti-colored tufts of yarn tied into 130

a backing fabric, and having changes in the coloring of the pattern effected upon single ends of the yarn, substantially as specified.

2. A woven fabric consisting of two backing webs and parti-colored warp threads crossing from one web to the other, and having color units of minimum length extending only from one web to the other, substantially as specified.

10 3. A woven fabric having a cut pile composed of parti-colored tufts of yarn, each formed around a single weft thread, a stuffer warp thread, a pair of binder warp threads, and pairs of binder and separator weft threads, alternating with each other, substantially as specified.

15 4. The mode herein described of producing

two similarly patterned cut pile fabrics, said mode consisting in first printing the pile warp threads as for a single fabric, then inter-weaving said pile warp threads with separated backing webs in such a manner that the single units of color in the pile warp threads will cross from web to web and then severing the cross warp threads midway between the backing webs.

20 In testimony whereof, I have signed my name to this specification, in the presence of two subscribing witnesses.

25 ALFRED HEALD.
